GARMENT SUPPORT

Stella Dunn Kennedy, New Orleans, La.

Application March 23, 1938, Serial No. 197,711

1 Claim. (Cl. 241—1)

This invention relates to combined corset and hose supporters, the primary object of the invention being to provide a supporter which will prevent the corset from riding up, and at the same time provide a hose supporter which will securely hold the hose against wrinkling.

Another object of the invention is to provide a supporter which will relieve the stockings of undue strain usually directed thereto when the corset which carries the usual supporters, rides up, thereby eliminating stocking runs usually resulting from excessive strain directed to the stockings.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a view illustrating the application of the supporter, constructed in accordance with the invention.

Figure 2 is a perspective view of the supporter.

Figure 3 is a sectional view taken on line 3—3 of Figure 2.

Figure 4 is an elevational view illustrating the clasp employed in securing the supporter to the stocking.

Figure 5 is a sectional view taken on line 5—5 of Figure 4.

Referring to the drawings in detail, the reference character 5 designates the usual corset, to which the supporter forming the subject matter of the present invention is connected.

The supporter includes an upper band 6 constructed of elastic material, the band being in the form of a strap, the ends thereof being connected by means of the clasp 7, whereby the band may be readily and easily positioned around the leg of the user, at a point above the knee. Extending upwardly from the band 6 are straps 8 which are constructed of elastic material and formed with tabs 9 which have openings for the reception of the headed fastenings 10 which are shown as supported at the lower ends of the straps 11, that in turn are secured along the lower edge of the corset 5, as clearly shown by Figure 1 of the drawings.

Removably connected with the band 6, is a lower leg encircling band 12, constructed of elastic material, the band being also in the form of a strap, the ends thereof being connected by means of the hook and eye fastener 13.

Straps indicated by the reference character 14 are constructed of elastic material and have their lower ends secured to the band 12, the upper ends of the straps 14 being provided with hooks 15 adapted to hook into the loop members 16 carried by the band 6 whereby the band 12 is removably secured to the band 6. These straps are of an adjustable character, so that the distance between the bands 6 and 12, may be regulated to suit the requirements of the user. It will of course be understood that in the use of the supporter, the band 12 encircles the leg of the user at a point below the knee.

Clasps 17 are secured to the band 6, and are so positioned that they will grip the upper edge of the stocking or hose worn by the person using the supporter.

From the foregoing it will be seen that due to the construction shown and described, the strap 12, being positioned below the knee of the user, will not creep upwardly, and will hold the band 6 and corset connected therewith, downwardly against the corset riding up, while the person using the supporter is walking.

Because the strap 12 and band 6 are held against upward movement, it will be obvious that the hose or stocking connected with the band 6, through the clasps 17, will not be subjected to excessive strain, as would be the case if the band 6 or supporters which usually connect with the hose and are carried by the corset, should move upwardly, due to the riding up of the corset.

I claim:

A supporter of the class described comprising a wide upper band adapted to encircle the leg above the knee, and a substantially narrow band adapted to encircle the leg below the knee, adjustable straps connecting the bands, straps extending upwardly from the upper band and adapted to connect with the corset worn by the person using the supporter, and clasps secured to the upper band at points adjacent to the lower ends of the straps extending upwardly from the upper band, and said clasps extending downwardly to connect with the stockings of the wearer.

STELLA DUNN KENNEDY.
